Primary Examiner—James Gandy*Assistant Examiner*—Daniel Bui(74) *Attorney, Agent, or Firm*—Leydig, Voit & Mayer, Ltd.**(57) CLAIM**

The ornamental design for the rectangular container with lid, as shown and described.

DESCRIPTION

FIG. 1 is a perspective view of the container and lid with the door in the closed position;

FIG. 2 is a perspective view similar to FIG. 1, but with the door in an open position;

FIG. 3 is a top view of the container and lid as shown in FIG. 1;

FIG. 4 is a top view of the container and lid as shown in FIG. 2;

FIG. 5 is a front view of the container and lid as shown in FIG. 1;

FIG. 6 is a rear view of the container and lid as shown in FIG. 1;

FIG. 7 is a front view of the container and lid as shown in FIG. 2;

FIG. 8 is a bottom view of the container and lid as shown in FIG. 1;

FIG. 9 is a side view of the container and lid as shown in FIG. 1, taken from the right;

FIG. 10 is a side view of the container and lid as shown in FIG. 2, taken from the right;

FIG. 11 is a cross-sectional view of the container and lid as shown in FIG. 10;

FIG. 12 is a perspective view of another embodiment of the container and lid with the door in the closed position;

FIG. 13 is a front view of the container and lid as shown in FIG. 12;

FIG. 14 is a rear view of the container and lid as shown in FIG. 12; and,

FIG. 15 is a side view of the container and lid as shown in FIG. 12, taken from the right.
